INFUSION PACKAGE WITH A NON-TANGLING STRING-HANDLE AND TAG

Hans O. Irmscher, Uniondale-Hempstead, N. Y., assignor to National Tea Packing Company, Inc., Long Island City, N. Y., a corporation of New York

Application September 14, 1954, Serial No. 455,979

3 Claims. (Cl. 99—77.1)

This invention relates to the manufacture of filled containers or bags and more particularly is directed to infusion packages, such as, tea or coffee bags manufactured and finished for delivery to users from envelopes and cartons with non-tangling string-handles terminated by a tag or the like articles, and the method of arranging the string-handle and tag in a non-tangling shortened position.

Among the objects of the invention is the general improvement of filled containers or bags with non-tangling arranged string-handles and tags as applied to inexpensive articles of manufacture, which shall comprise a simple arrangement of parts that is easy and cheap to produce, which shall be capable of being manufactured in quantity production on automatic super high speed packaging machines, which shall have an intermediate portion of the string-handle, adjoining an end thereof anchored to a heat-sealed closure of said package, temporarily retained in a slip looped configuration engaging said anchored end to eliminate possible tangling in cartoning or wrapping such infusion packages individually for use, which shall be reliably held in compact condition yet have the string-handle positively released from said temporary retention by simply applying a pulling or lifting force on the tag, which shall avoid putting tearing strains on the package closure or other package structures, which shall provide a neat and attractive package, and which shall be practical and efficient to a high degree in use.

Other objects of the invention will in part be obvious and in part hereinafter pointed out.

The invention accordingly comprises the steps of the manufacturing method and features of constructions, combinations of elements and arrangements of parts which will be exemplified in the method and constructions hereinafter disclosed, the scope of the application of which will be indicated in the claims following.

In the accompanying drawing in which possible illustrative embodiments of the invention are shown:

Figs. 1 and 2 are enlarged front and rear elevational views, respectively, of a tea bag manufactured with a non-tangling temporarily retained looped configuration string-handle and tag for cartoning and as delivered to the consumer for use in a sanitary manner.

Fig. 3 is a cross-sectional view taken on line 3—3 in Fig. 1.

Fig. 4 is a perspective view of the tea bag shown in Figs. 1 and 2 with the string-handle and tag extended ready for brewing.

Fig. 5 is a perspective view similar to Fig. 4, but of a modified tea bag utilizing the heat-sealed top closure seam flanges as an attachment means for the string-handle instead of the staple shown in Figs. 1 to 4, inclusive.

Figs. 6 and 7 are enlarged front and rear elevational views, respectively, of the modified form of tea bag shown in Fig. 5 with the string-handle and tag arranged in a

2

non-tangling temporarily retained looped configuration similar to that shown in Figs. 1 and 2, and

Fig. 8 is a cross-sectional view taken on line 8—8 in Fig. 6.

In manufacturing infusion packages such as tea bags and the like, it is found desirable and most practical to include some form of handle to manipulate the tea bag during the brewing operation which is best carried on in a cup and also to provide a tag which bears a legend or trademark of the manufacturer, grade of tea, etc. In order to eliminate tangling of the string-handle and tag which often results in accidental tearing of the bag when cartoning and handling when individually removed for use and to provide a neat and attractive tea package delivered to the user, various temporary retaining means have been devised.

The present invention, like those shown and described in my previous Patent No. 2,490,057, granted December 6, 1949, and my co-pending application, Serial No. 306,764, filed August 28, 1952, is intended to provide a practical construction for producing an infusion package with a non-tangling string-handle.

Referring in detail to the drawing, 10 denotes a filled infusion package embodying the invention constructed in the form of a square, that is, pillow-shaped, tea bag body portion 11 provided with a non-tangling string-handle 12 and tag 13 temporarily retained in a slip looped configuration engagement with an anchored string-handle end 12a made readily releasable by simply applying a pulling or lifting force without putting tearing strains on heat-sealed top closure seam flange 11a of said body portion 11 on which the string-handle end 12a is anchored by staple 14.

As is clear from Figs. 1 to 4, tea ball 10 may have body portion 11 thereof made of a suitable thin filter sheet material strip folded over on itself to provide a rounded bottom edge 11b forming superimposed layer portions to provide front and rear flattened sides 11c and 11d, respectively, of body portion 11, said sides 11c and 11d being secured along the marginal areas on the remaining three edge portions with seam flange 11a forming said top closure extending between spaced apart parallelly aligned seam flanges 11e and 11f to completely seal contents T in body portion 11.

Tea bag body portion 11 may be constructed of a suitable foraminous sheet material, as for example, filter paper, coated for heat-sealing more fully described in my said Patent No. 2,490,057.

Unlike the construction of the non-tangling string-handle retaining means disclosed in my said Patent No. 2,490,057, heat-sealed top closure seam flange 11a is left unslit and otherwise uncut so that tearing strains to which the package structure may be subjected in use at and about anchoring staple 14 can be reduced to a minimum in the construction embodying the invention.

String-handle end 12a is attached to top closure seam flange 11a by staple 14 in a double, overcast locked anchorage, that is, the free end of string-handle 12 passes under staple 14 on body portion rear side 11d, then loops over the extreme edge of top closure seam flange 11a as at overcast portion 12b and again passes under staple 14 on body portion front side 11c to complete the double anchorage.

In the non-tangling shortened position shown in Figs. 1, 2, and 3 elongated mid-portion 12c of string-handle 12, after leaving said double anchorage, extends under, that is, through overcast portion 12b in a hitch, that is, slip knot configuration at 12e and over said extreme edge of seam flange 11a to lie against body portion rear side 11d as large loop 12d. The end portion 12f of string-handle 12 adjacent tag 13 repasses through overcast portion 12b and over said extreme edge of seam flange 11a

completing said slip knot configuration to position tag 13 flat against body portion front side 11c.

Tags 13 may be attached to the end of string-handle 12 beyond end portion 12f in any suitable manner, such as, by staples or, as here shown, tag 13 is of relatively thin double width resin coated paper stock folded over and heat-sealed together onto string-handle 12 as fully described in my said co-pending application Ser. No. 306,764.

The invention may be practiced by applying string-handles 12 with tags 13 to top closure seam flanges 11a of tea bag body portions 11 each heat-sealed with contents T by means of staples 14 with said double anchorages providing string-handle overcast portions 12b on a high speed tea bag manufacturing apparatus fully described in my said co-pending application Ser. No. 306,764, after which, each string-handle mid-portion 12c is inserted through each of said overcast portions 12b finishing filled tea bag packages 10 with the non-tangling shortened string-handles and tags as shown in Figs. 1, 2 and 3 and thereby permitting unobstructive advancement through said manufacturing apparatus for automatic cartoning and delivering tea bag packages 10 to the user in a non-tangled shortened condition.

The tea bag package 10 may be removed from an envelope or carton container without fingering body portion 11 by simply picking up tag 13 so that the weight of the filled package readily pulls large loop 12d through overcast portion 12b from its temporary frictional retained position permitting suspension of body portion 11 by the entire length of string-handle 12 as shown in Fig. 4 thereby aiding as a sanitary method for manipulating in brewing in the well understood manner.

The method embodying the invention will now be apparent. After forming filled tea bag body portion 11 with heat-sealed top closure seam flange 11a, string-handle 12 with tag 13 previously attached to one end thereof is secured to seam flange 11a by arranging the string-handle end 12d opposite tag 13 in an overcast position and stapling same thereto to serve as said double anchorage with string-handle overcast portion 12b extending over the extreme edge of seam flange 11a. String-handle midportion 12c is then inserted under overcast portion 12b and drawn through in a frictionally retained slip knot condition until string-handle large loop 12d is positioned to lie flat against rear side 11d with tag 13 against front side 11c.

A modified form embodying the invention is shown as tea bag package 20 in Figs. 5, 6, 7 and 8 to comprise body portion 21 provided with a rounded bottom edge 21b forming superimposed layer portions as front and rear flattened sides 21c and 21d, respectively, of body portion 21 and side seam flanges 21e and 21f for containing contents T, all similar to the corresponding parts of tea bag package 10.

Instead of utilizing a staple for attaching string-handle end 22a, the latter in a serpentine configuration is placed between an upper margin portion of sides 21c and 21d and heat-sealed therein during the bag closing operation forming heat-sealed top closure seam flange 21a as a string-handle anchorage.

In order to provide a non-tangling string-handle retaining means embodying the invention, the serpentine configuration of string-handle end 22a is so arranged when heat-sealed into seam flange 21a as to provide an auxiliary loop portion 22b extending beyond the extreme edge of top closure seam flange 21a, as is clear from Fig. 5.

In the non-tangling shortened position shown in Figs. 6, 7 and 8, elongated mid-portion 22c of string-handle 22 after emerging for a second time from seam flange 21a extends in slip knot configuration as at 22e through auxiliary loop portion 22b and over said extreme edge of seam flange 21a to lie against body portion rear side 21d as large loop 22d similar to large loop 12d of package 10. The end portion 22f of string-handle 22 adja-

cent tag 23 repasses through auxiliary loop portion 22b and over said extreme edge of seam flange 21a completing said slip knot configuration to position tag 23 flat against body portion front side 21c similar to tag 13 in package 10.

In the method of manufacturing tea bag package 20, string-handle end 22a is positioned between the upper margins of front and rear sides 21c and 21d, respectively, in a serpentine configuration for forming said auxiliary loop portion 22b and is then anchored therebetween simultaneously with the heat-sealing of the top closure of filled body portion 21 forming seam flange 21a. String-handle mid-portion 22c is then inserted through auxiliary loop portion 22b and drawn through in a frictionally retained slip knot condition until string-handle large loop 22d is positioned to lie flat against rear side 21d with tag 23 against front side 21c in a manner similar to the insertion of string-handle mid-portion 12c under overcast portion 12b in forming package 10.

Tea bag package 20 may be removed from its envelope or carton container without fingering body portion 21 in the same manner as hereinbefore described for package 10.

It is thus seen that there are provided improved infusion packages with non-tangling string-handles and tags and a method for manufacturing same in which the several objects of the invention are achieved and which are well adapted to meet the conditions of practical use.

As various possible embodiments might be made in the above invention, and as various changes might be made in the constructions and method above set forth, it is to be understood that all matters herein set forth or shown in the accompanying drawings are to be interpreted as illustrative and not in a limiting sense.

Having thus described my invention, I claim as new and desire to secure by Letters Patent:

1. In an infusion package having a string-handle terminated by a tag, a non-tangling positioning construction for said string-handle and tag comprising a top closure seam flange of a flat-pillow-shaped body portion of said package, an end portion of said string-handle opposite said tag anchored to said top closure seam flange and provided with a small loop extending beyond the seam flange edge, an elongated mid-portion of said string-handle between said string-handle anchorage and tag extending in slip knot configuration from a front side of said body portion through said small loop and over said seam flange edge and positioned as a large loop lying flat against a rear side of said body portion, a portion of said string-handle adjacent the tag being repassed through said small loop and over the flange edge completing said slip knot configuration to position the tag flat against said body portion front side whereby said string-handle and tag are temporarily retained in said flat position.

2. In an infusion package having a string-handle terminated by a tag, a non-tangling positioning construction for said string-handle and tag comprising a top closure seam flange of a flat pillow-shaped body portion of said package provided with a staple, an end portion of said string-handle opposite said tag double anchored by the staple to provide an overlocking portion extending about the edge of said flange, an elongated mid-portion of said string-handle between said staple and tag extending through said overlocking portion in slip knot configuration from a front side of said body portion and over said edge of the flange and positioned as a loop lying flat against a rear side of said body portion, a portion of said string-handle adjacent the tag being repassed through said overlock portion and over the flange edge completing said slip knot configuration to position the tag flat against body portion front side whereby said string-handle and tag are temporarily retained in said flat position.

3. The infusion package defined in claim 1 in which said top closure seam flange is a heat-sealed joint, said

string-handle anchorage being of a serpentine configuration of the string-handle end heat-sealed in said seam flange joint, and said small loop being a portion of said serpentine configuration.
